UNITED STATES PATENT OFFICE.

EUGENE A. FLEMING, OF SOUTH BRAINTREE, MASSACHUSETTS, ASSIGNOR OF ONE-HALF TO BERTRAM T. MARTIN, OF CHELSEA, MASSACHUSETTS.

METHOD OF MAKING SHOES.

1,150,181.

Specification of Letters Patent. Patented Aug. 17, 1915.

Application filed December 5, 1914. Serial No. 875,701.

To all whom it may concern:

Be it known that I, EUGENE A. FLEMING, a citizen of the United States, residing at South Braintree, county of Norfolk, State 5 of Massachusetts, have invented an Improvement in Methods of Making Shoes, of which the following description, in connection with the accompanying drawing, is a specification, like characters on the drawing 10 representing like parts.

This invention relates to a novel process for making welt shoes, and the objects of the invention are to provide a welt shoe which has great flexibility, in which the 15 insole is free from ridges or shoulders such as are frequently caused by the channeling of the insole; which is so constructed that the lasting operation is greatly facilitated, and which has other advantages, all as will 20 be more fully hereinafter described and then pointed out in the claims.

In order to give an understanding of my invention, I have illustrated in the drawings a selected embodiment thereof which discloses the various steps of manufacture.

Figure 1 is a cross sectional view through the upper before the welt is sewed thereto; Fig. 2 is a similar view showing the shoe lasted, the welt sewed to the upper and the 30 insole secured in position; Fig. 3 is a cross-sectional view through the completed shoe; Fig. 4 is a view showing the shoe in perspective before the outsole is sewed thereto; Fig. 5 is a view showing the piece of 35 material from which the welt and insole are made; Fig. 6 is a view showing the outsole.

My improved shoe is of that type in which the welt extends clear around the upper and in manufacturing my shoe, I propose to employ 40 an endless seamless welt which is cut to the desired shape from a flat piece of sheet material and to employ an insole having an edge contour corresponding to the inner edge contour of the endless seamless welt. In making my improved shoe the 45 welt is sewed to the marginal edge of the upper, the insole is then applied to the shoe and secured in place, and the outsole is subsequently sewed or otherwise fastened to the 50 welt. By reason of the fact that the insole employed has an edge contour corresponding in shape and size to the inner edge contour of the welt, the welt and inner sole 55 will accurately fit together in the completed shoe, thus facilitating the assembling of the

parts and the lasting of the upper. Further, the fact that the welt which is used is an endless seamless welt strip cut to the proper shape from sheet material facilitates the operation of lasting due to the fact that 60 the tendency of the welt when it is sewed to the upper is to cause the marginal edge of the upper to conform to the desired shape of the shoe which is determined by the last.

In the drawings 1 designates the upper 65 which may be of any suitable shape or material and of any desired size or style depending on the character of the shoe to be made. In making a shoe I provide a continuous endless welt strip 2 which is sewed 70 to the marginal edge 3 of the upper and extends clear around the upper. This welt strip is cut to the desired shape directly from a flat piece of sheet material and, therefore, it naturally retains its shape and 75 position. After the welt strip has been sewed to the marginal edge of the upper an insole 4 is secured in place, and this may be done during the lasting operation if desired. The insole 4 is secured to the upper 80 by means which do not necessitate the employment of a rib or lip on the insole to receive the inseam stitches as usual in Goodyear welt shoes.

In my improved shoe I propose to secure 85 the upper in place by means of the lining 5, said lining being herein shown as provided with the portions 6 that extend beyond the marginal edge of the upper and which are folded over and secured to the 90 insole 4, as shown in Fig. 2. These extended portions 6 of the lining may be fastened to the insole in any suitable way, but I will preferably simply cement them to the sole as this will ordinarily constitute a 95 sufficiently strong structure. Some form of fastening devices might be used for this purpose if desired. The insole 4 has a special relation to the welt strip 2 in that the exterior contour of the insole corresponds 100 in shape and size to the interior edge contour of the welt strip 2 so that when the parts of the shoe are assembled, as shown in Figs. 2 and 3, the insole and welt will accurately fit each other. After the insole and 105 welt have been secured in place the outsole 7 is secured to the welt by any suitable means, such as stitching 8. This particular relation between the shape of the insole and the interior shape of the welt may be se- 110

cured in any suitable way. One convenient way, however, is to cut the welt strip and the insole from the same piece of material, as shown in Fig. 5, that is, a piece of sheet material 10 of the proper shape can be cut along the line 11 thereby to cut from the piece a marginal or peripheral strip which constitutes the welt strip 2, this operation leaving the central part 4 which is used 5 for the insole. In this way the inner edge contour of the welt and the exterior edge contour of the insole are exactly similar in size and shape so that when the two parts are brought together in the shoe they will 10 accurately fit each other.

It is possible to make the piece 10 from which the insole 4 and welt strip 2 are cut of the same shape and size as the outsole 7, and in fact I prefer to have the pieces 7 and 20 10 of exactly the same contour because by so doing the outsole when applied to the welt of the shoe will accurately fit the welt and a better shoe can be made. Further, by means of this the cost of manufacture is cheapened 25 as the pieces 7 and 10 can be cut from leather or other material by means of the same die. I may also provide for cutting the welt strip 2 and insole 4 simultaneously from a piece of sheet material by means of a die 30 30 having two cutting edges, one to cut along the line 11 and the other to cut the exterior contour of the welt strip. However, the particular way in which the welt strip and sole are cut from the sheet material is not essential 35 to my invention, the important point being that when formed the exterior edge contour of the insole corresponds to the interior contour of the welt strip. Another advantage which is incident to the above-described 40 construction lies in the fact that the form of welt used facilitates the lasting operation. It will be noted that the interior contour of the welt strip is the same as the exterior contour of the insole and hence when the shoe 45 is lasted and the upper is drawn into the proper position, the natural shape which the welt assumes at the points 14 will tend to draw the sides of the upper closely against the last, thus, making it much easier for the 50 operator to bring the upper into close contact with the last. Further, since the insole is secured to the upper by means of the extending portion 6 of the lining instead of by inseam stitching the insole is free from 55 any ribs or lips and the shoe presents a much smoother interior than the ordinary welt shoe.

The dies which are used for cutting out the outsole 7 and the piece 10 may if desired 60 be of such a shape as to form positioning projections 16 on some portion of the periphery, as for instance, at the toe and heel, as shown in Figs. 5 and 6, the projections on the pieces

7 and 10 having similar positions. The advantage of these is that they assist the operator in properly positioning the outsole upon the lasted shoe for since the projections 16 on the outsole correspond in position to the projections 16 on the piece 10 the proper positioning of the outsole on the shoe involves 70 merely bringing the projection 16 thereon into line with those on the welt.

My improved shoe is extremely flexible and is easy on the foot. It can be manufactured cheaply and has many other advantages. 75

While I have illustrated herein a selected embodiment of the invention, I do not wish to be limited to the constructional details shown.

I claim:

1. The process of making a shoe which consists in cutting an endless peripheral welt strip from a sole-shaped piece of sheet material, sewing said endless welt strip to the marginal edge of a shoe upper, securing to the upper as an insole the central portion of said sole-shaped piece remaining after the welt strip is cut therefrom, and sewing an outsole to the welt. 85

2. The process of making a shoe which consists in providing an insole of the proper shape, forming from a piece of sheet material an endless welt strip having an inner edge contour corresponding to the outer edge 95 contour of the insole, securing the welt and insole to the upper and securing an outsole to the welt.

3. The process of making a shoe which consists in forming from a single sole-shaped 100 piece of sheet material both an endless welt and an insole by severing said piece along a line adjacent the periphery and having a contour corresponding to that of the insole desired, attaching said welt and insole to the upper with the edge of the upper interposed between the inner edge of the welt strip and the outer edge of the insole and securing an outsole to the welt.

4. The process of making a shoe which 110 consists in forming from a single sole-shaped piece of sheet material both an endless welt and an insole by severing said piece along a line adjacent the periphery and having a contour corresponding to that of the insole 115 desired, attaching said welt and insole to the upper and attaching an outsole to the welt.

In testimony whereof, I have signed my name to this specification, in the presence of 120 two subscribing witnesses.

EUGENE A. FLEMING.
